(57) **CLAIM**

The ornamental design for a reader cradle for a surgical stand, as shown and described.

DESCRIPTION

FIG. 1 is a top, rear, left-side perspective view of a reader cradle for a surgical stand;

FIG. 2 is a rear view thereof;

FIG. 3 is a front view thereof;

FIG. 4 is a right-side view thereof;

FIG. 5 is a left-side view thereof;

FIG. 6 is a top view thereof;

FIG. 7 is a bottom view thereof;

FIG. 8 is a bottom, front, right-side perspective view thereof;

FIG. 9 is an enlarged front, partial view indicated by number 9 in FIG. 3; and,

FIG. 10 is an enlarged perspective, partial view indicated by number 10 in FIG. 8.

In the drawings, the dash-dash broken lines depict portions of the reader cradle for a surgical stand and form no part of the claimed design. The dot-dash broken lines depict the boundary lines of the enlarged partial views and form no part of the claimed design.

1 Claim, 9 Drawing Sheets
